US0D1073631S

(12) **United States Design Patent** (10) **Patent No.:** **US D1,073,631 S**
Choi (45) **Date of Patent:** **** May 6, 2025**

(54) **TRIP DEVICE FOR CIRCUIT BREAKER**

(71) Applicants: **LS ELECTRIC CO., LTD.**, Anyang-si (KR); **LS ELECTRIC (Lishui) CO., LTD.**, Zhejiang (CN)

(72) Inventor: **Minho Choi**, Anyang-si (KR)

(73) Assignees: **LS ELECTRIC CO., LTD.**, Anyang-si (KR); **LS ELECTRIC (LISHUI) CO., LTD.**, Zhejiang (CN)

(**) Term: **15 Years**

(21) Appl. No.: **29/900,889**

(22) Filed: **Aug. 25, 2023**

(30) **Foreign Application Priority Data**

Apr. 28, 2023 (KR) 30-2023-0016532

(57) **CLAIM**

The ornamental design for a trip device for circuit breaker as shown and described herein.

DESCRIPTION

FIG. 1 is a front perspective view of a trip device for circuit breaker showing the new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof, wherein.

Lines shown as broken lines form no part of the claimed design.

1 Claim, 8 Drawing Sheets
